(57) CLAIM

We claim the ornamental design for a luminaire for light treatments, as shown and described.

DESCRIPTION

FIG. 1 is a perspective view of a luminaire showing Applicant's new design;

FIG. 2 is a front view of the embodiment of FIG. 1;
FIG. 3 is a back view of the embodiment of FIG. 1;
FIG. 4 is a right view of the embodiment of FIG. 1;
FIG. 5 is a top view of the embodiment of FIG. 1; and,
FIG. 6 is a bottom view of the embodiment of FIG. 1.
The broken lines shown on the drawings depict portions of the light fixture that form no part of the claimed design.
